(57) CLAIM

The ornamental design for a luminaire, as shown and described.

DESCRIPTION

FIG. 1 is a perspective view of a luminaire of the present invention;

FIG. 2 is a left side elevational view of the luminaire of FIG. 1, the right, opposite, side of which is a mirror image thereof;

FIG. 8 is a left side elevational view of the luminaire of FIG. 7, the right, opposite, side of which is a mirror image thereof;
